Primary Examiner — Marie D. Fast Horse

Assistant Examiner — Josiah D. Parsons

(57) **CLAIM**

The ornamental design for a keyboard, as shown and described.

DESCRIPTION

FIG. 1 is a front perspective view of a first embodiment of a keyboard showing our new design;

FIG. 2 is a front view thereof;

FIG. 3 is a back view thereof;

FIG. 4 is a top view thereof;

FIG. 5 is a bottom view thereof;

FIG. 6 is a right view thereof;

FIG. 7 is a left view thereof;

FIG. 8 is a front perspective view of a second embodiment of a keyboard showing our new design;

FIG. 9 is a front view thereof;

FIG. 10 is a back view thereof;

FIG. 11 is a top view thereof;

FIG. 12 is a bottom view thereof;

FIG. 13 is a right view thereof;

FIG. 14 is a left view thereof;

FIG. 15 is a front perspective view of a third embodiment of a keyboard showing our new design;

FIG. 16 is a front view thereof;

FIG. 17 is a back view thereof;

FIG. 18 is a top view thereof;

FIG. 19 is a bottom view thereof;

FIG. 20 is a right view thereof;

FIG. 21 is a left view thereof;

FIG. 22 is a front perspective view of a fourth embodiment of a keyboard showing our new design;

FIG. 23 is a front view thereof;

FIG. 24 is a back view thereof;

FIG. 25 is a top view thereof;

FIG. 26 is a bottom view thereof;

FIG. 27 is a right view thereof; and,

FIG. 28 is a left view thereof.

1 Claim, 20 Drawing Sheets
